DESIGN FOR A HEATING STOVE

Wilbur Henry Adams and Charles J. Kessler,
Cleveland Heights, Ohio, assignors to Perfec-
tion Stove Company, Cleveland, Ohio, a cor-
poration of Ohio

Application June 20, 1935, Serial No. 57,359

Term of patent 14 years

To all whom it may concern:

Be it known that we, Wilbur Henry Adams and Charles J. Kessler, citizens of the United States, residing at Cleveland Heights, in the county of Cuyahoga and State of Ohio, have invented a new, original, and ornamental Design for Heating Stoves, of which the following is a specification, reference being had to the accompanying drawing, forming part hereof, and wherein the figure is a perspective view of a heating stove showing our new design. The side opposite that shown in the drawing is substantially the same as the

one revealed and the portion of the casing that is shown in light lines is of light transmitting material. A very distinctive characteristic of the design is the contrast resulting from the use of light transmitting material for the portion mentioned and metal for the remainder of the structure.

We claim:

The ornamental design for a heating stove, as shown and described.

WILBUR HENRY ADAMS.
CHARLES J. KESSLER.
